DISCONNECT SWITCH

Aldo M. de Bellis, Summit, N. J., assignor to Rail-
way and Industrial Engineering Company, a
corporation of Delaware

Application March 1, 1938, Serial No. 193,379

7 Claims. (CL 200—48)

This invention relates to disconnect switches and more particularly to disconnect switches for use with or forming a part of a bus system of the type in which each phase is completely enclosed in an individual grounded duct or casing.

Objects of this invention are to provide enclosed disconnect switches of simple and rugged design, the moving blade and jaws of each switch being so related as to form, in effect, a part of the rigidly supported bus when the switch is in closed position. An object is to provide a disconnect switch having jaw members rigidly supported in a metal housing and adapted to be secured to the axially aligned ends of the bus, and having a blade member mounted for translation into axial alignment with the bus sections to engage the jaw members or, alternatively, into a position parallel to and remote from the axis of the aligned bus sections. An object is to provide a bus type of disconnect switch in which each of a pair of jaw members is supported in an individual heavy frame by three insulators, and the movable switch blade is carried by a pair of insulators that lie in the transverse planes of the two groups of jaw member insulators, the arrangement of insulators being such that the switch, when closed, is rigidly mounted coaxial with the bus sections. A further object is to provide a multiple phase disconnect switch for use in an enclosed bus system, the switch having a complete metallic housing for each phase of the bus system, the jaw members of the switch being rigidly supported at one end section of the associated housing for connection to the ends of the bus sections of that phase, and the other end section of each housing providing a space into which the double-break switch blades may be simultaneously withdrawn by a common operating mechanism.

These and other objects and advantages of the invention will be apparent from the following specification when taken with the accompanying drawings in which:

Fig. 1 is a plan view of an embodiment of the invention;

Fig. 2 is an elevation of the same as viewed from the left of Fig. 1;

Fig. 3 is a longitudinal section through one switch unit and its housing, the housing and the switch jaw at the left being shown approximately in central section and the switch jaw at the right being shown in elevation; and

Fig. 4 is an end view, looking axially into the switch housing, the end plate of the housing being omitted.

The particular embodiment of the invention

herein illustrated is adapted for use with or in a bus system such as described and claimed in the copending application of Harold H. Rudd, Serial No. 167,639, filed Oct. 6, 1937, "Electrical bus systems". The bus system therein described includes insulator frames within which the bus of each phase is supported by a plurality of radially extending insulators, and duct plates that extend between the insulator frames to form a separate duct or housing for each phase. The switches of this invention include housings which are built into the duct system of the protected bus sections of the separate phases.

The switches may be arranged at any angle but, for convenience of description, it will be assumed that Fig. 1 is a plan view of a disconnect switch which joins two horizontal runs of a three phase bus system. The end elevation, Fig. 2, shows the housings in appropriate position for insertion between two vertical sections of bus.

In Fig. 1, the housings of the switches for the separate phases are identified generally by the reference characters A, B and C, the housings being held in adjacent but spaced relation by a plurality of straps or angle bars 1. Each housing includes opposite walls or plates 2 having openings for the entrance of the bus, and ring flanges 3 are secured to walls 2 about the openings to support the ends of duct-forming plates such as described in the Rudd application.

The exact construction of the housing is not important so long as it is relatively rigid and substantially air tight. As shown, the basic framework of the housing comprises a welded frame of angle bars 4 which extends around the edges of the rectangular body of the housing. The plates 2 are secured to the frame angles 4 by bolts, not shown, and the top, bottom and end plates 5, 6, 7, respectively, are connected to the frame in like manner.

A rigid flanged plate 8 extends across the interior of the housing and is secured to the angle framework 4, Fig. 3. A pair of heavy frames 9 of approximately U-shape are secured between the transverse plate 8 and the bottom section of the angle framework, and the plate 8 has openings 10 in alignment with the open upper ends of the U-frames. The central planes of these frames 9 are transverse to the axis of the openings in the housing walls 2, and the frames are spaced inwardly from those walls.

Insulators 11 are secured to the bottom and legs of the U-frames 9 to support the jaw elements of the switch in alignment at the centers of the two frames. Each jaw member includes

a tubular sleeve 12 of rectangular cross-section which has openings for receiving screws 13 that secure the sleeve to the metal inserts 14 in the ends of the insulators. A plurality of plates 15 extend through each sleeve 12 and are held in spaced parallel relation by studs 16 and spacers 17, 18. The inner ends of the sleeves 12 and plates 15 are sharply inclined to the axis of the sleeves 12, and the ends of the plates 19 of the sleeves 12, and the ends of the plates 19 of the switch blade are similarly inclined. The blade members 19 have contact bosses 20 for engagement with similar bosses, not shown, on plates 15 of the jaw members, and the ends of plates 15 are slotted and reinforced by the fingers of a spring plate 21.

The plates 19 are secured in parallel spaced relation to heavy bars 22 by bolts 23 and spacers in 24, and the bars 22 are pinned to inserts 25 in the lower ends of insulators 26.

The insulators 26 are in the transverse planes of the sets of insulators 11, and the upper ends of insulators 26 are secured to a blade carriage 27 that has end hubs 28 guided on parallel rods 29 which extend between the transverse plate 8 and a top plate 30. The carriage 27 is supported by the threaded stems 31 that are above and coaxial with the insulators 26, the mechanical connection being made through nuts 32 on the stems and sleeves 33 which are pivoted on the nuts and secured to the carriage. The threaded stems extend upwardly through the central section 30' of the top plate 30 and are journaled in boxes 34 that are mounted on the end plate.

Bevel gears, not shown, are mounted on the upper ends of the threaded stems 31 and on the ends of cross-shafts 35, 36. Shaft 35 of switch unit A is journaled in a plate 37 that is fixed to an angle bar 1, and the shaft 35 carries an operating member which, as shown, may be a manually operable wheel 38. Cross-shafts 36 transmit rotary motion between the ends of the threaded stems 31 of each switch unit, and motion is transmitted from a stem of one unit to a stem of an adjacent unit by bevel gears, not shown, in the boxes 34, stub shafts 39, and insulating shaft sections 40 that are connected between the stub shafts 39 by flexible joints 41. The wheel 38 is normally locked against rotation by a bar 42 that is locked in place by a key-controlled unit 43. This interlock does not, however, form any part of the present invention.

Reverting to Fig. 3, it will be noted that the outer ends of the contact plates 15 of the jaw members have openings 15' for making bolted connections to the ends of the bus sections at opposite sides of the disconnect switch. The switch jaws thus form extensions of the bus sections and, when the switch is closed, the contact plates 19 of the blade are meshed with plates 15 of the jaws and extend between the bus sections. Each end of the switch is rigidly supported against transverse stresses by four insulators that are uniformly spaced about the switch in a plane transverse to the axis of the bus and switch. Current surges which tend to force the switch laterally are resisted by compression stresses in the insulators and the construction is therefore strong mechanically as the usual porcelain insulators are freed from tension and cantilever stresses.

The disconnect switches are to be used, as is customary, to isolate a section of the bus system after the circuit breakers are opened. Some features are useful in other relations and it is therefore to be understood that there is considerable

latitude in the design and construction of disconnect switches which fall within the spirit of my invention as set forth in the following claims.

I claim:

1. In a disconnect switch, a pair of jaw members in spaced axial alignment, a plurality of insulators supporting each jaw member against transverse displacement, said insulators for each jaw member being in a plane transverse to the axis of the jaw members, a blade member, insulators carrying said blade member and located in the transverse planes of the insulators of the respective jaw members, and means for displacing said blade member and insulators to carry said blade member into and out of engagement with said jaw members; the several insulators in each of the said transverse planes being spaced circumferentially of the axis of the jaw member to restrict the stresses in said insulators to compression stresses when current surges tend to displace said switch members transversely.

2. In a disconnect switch, a pair of U-frames in spaced parallel relation, a set of three insulators extending from the base and legs of each frame towards the center of the frame, jaw members supported in axial alignment by the respective sets of insulators, a blade frame and operating means for moving the same towards and away from the plane of the open ends of said U-frames, a pair of insulators on said blade frame and in substantially axial alignment with the insulators carried by the bases of the respective U-frames, and a switch blade carried by said pair of insulators.

3. In a disconnect switch as claimed in claim 2, jaw members comprising plates having end surfaces sharply inclined to the direction of movement of the switch blade, the ends of the switch blade being correspondingly inclined.

4. The invention as claimed in claim 2, where- in each jaw member comprises a short tubular member of rectangular cross-section, means for securing the tubular members to the insulators of the associated U-frame, and a plurality of plate members extending through and supported in spaced parallel relation by each tubular member, the outer ends of each plate member being apertured to facilitate connection to the adjacent bus section.

5. A disconnect switch comprising a pair of spaced parallel frames of approximately U-shape, a rigid plate member extending across and secured to the open ends of said frames, said plate member having openings therethrough corresponding to the open ends of the frames, jaw members within and aligned axially at substantially the central points of the U-shaped frames, insulators supporting each jaw member within its frame, a blade carriage, means including said rigid plate member supporting said blade carriage for movement toward and away from said jaw members, a switch blade, and insulators secured to said carriage and extending into the open ends of said U-shaped frames to support said switch blade.

6. A disconnect switch as claimed in claim 5, wherein said supporting means comprises a pair of rods, and said blade carriage has hubs slideable on said rods for the guiding of said blade carriage.

7. A disconnect switch for use with an enclosed bus, said switch comprising a housing having aligned openings in opposite walls for the entrance of the ends of bus sections, flange members secured to the housing about said openings for

supporting the duct walls of the bus sections, a U-frame within said housing adjacent each apertured wall thereof, a jaw member within each frame at substantially the axis of the aligned openings, a plurality of insulators mounted on each frame to support the associated jaw member, a blade carriage and means mounting the same for movement toward and away from said

jaw members, insulators secured to said blade carriage in the planes of the insulators of the respective U-frames, a switch blade supported by the insulators of said blade frame, and means for moving said blade frame to carry said blade into and out of engagement with said jaw members. 5

ALDO M. DE BELLIS.
